UNITED STATES PATENT OFFICE.

ALLAN STIRLING, OF NEW YORK, N. Y., ASSIGNOR TO THE STIRLING COMPANY, OF CHICAGO, ILLINOIS.

STEAM-BOILER.

SPECIFICATION forming part of Letters Patent No. 479,678, dated July 26, 1892.

Application filed March 24, 1892. Serial No. 426,266. (No model.)

To all whom it may concern:

Be it known that I, ALLAN STIRLING, a citizen of the United States, residing at New York, in the county and State of New York, 5 have invented new and useful Improvements in Steam-Boilers, of which the following is a specification.

This invention relates to certain improvements on that class of steam-boilers which I 10 have described in Letters Patent No. 407,260, dated July 16, 1889, said improvements being pointed out in the following specification and claims, and illustrated in the accompanying drawings, in which—

15 Figure 1 is a vertical section in the plane $y-y$, Fig. 2. Fig. 2 is a horizontal section in the plane $x-x$, Fig. 1.

The letter A designates the mud-drum, and the letters $A' A^2$ the steam and water drums, 20 which are connected with the mud-drum by water-tubes $B' B^2$, respectively, and with each other by steam-pipes b' and water-pipes b^2 . With these drums I have combined a feed-drum A^3 , which connects with the mud-drum 25 by water-tubes B^3 and with the steam and water drum A^2 by steam-pipes b^3 . The feed-water is introduced into the feed-drum A^3 through the opening F.

W W is the brick setting. 30 D is the fire-brick arch of the furnace.

C is a fire-brick partition provided with a shelf c, and E is another fire-brick partition. d is a shelf, and M are the grate-bars.

As indicated by the arrows in Fig. 1, the 35 flame on striking the brick arch D is thrown between the water-tubes B' , leading from the drum A into the drum A' , and the partition C compels the flame to ascend between said water-tubes, and after it has passed the top 40 edge of this partition it descends, and as it strikes the shelf c it is compelled to pass down between the water-tubes B^2 , which lead from the drum A into the drum A^2 , until it reaches the bottom edge of the fire-brick partition E, 45 when it passes up between the water-tubes B^3 , which lead from the drum A into the feed-drum A^3 , said flame being compelled by the shelf d to pass between the tubes B^3 before it

can escape through the smoke-stack S. From this description it will be seen that by means 50 of the steam-pipes b^3 the pressure in the feed-water drum A^3 is the same as that in the drums $A' A^2$, and the feed-water descends through tubes B^3 and enters the mud-drum A in a heated state, and from this drum the 55 water rises through the tubes $B' B^2$ into the drums $A' A^2$, and it reaches these drums comparatively free from mud.

What I claim as new, and desire to secure 60 by Letters Patent, is—

1. A water-tube boiler consisting of a single mud-drum A, two elevated steam and water drums $A' A^2$, having their steam and water spaces respectively placed in communication, the water-tubes $B' B^2$, extending from 65 the mud-drum to the drums $A' A^2$, the feed-drum A^3 , the water-tubes B^3 , extending from the mud-drum to the feed-drum, and the pipes b^3 , connecting the feed-drum with one of the steam and water drums, substantially as de- 70 scribed.

2. A water-tube boiler consisting of a furnace structure, a single mud-drum A, the elevated steam and water drums $A' A^2$, having their steam and water spaces respectively 75 placed in communication, two sets of water-tubes $B' B^2$, directly connected at their upper ends with the steam and water drums and both sets connected at their lower ends with the single mud-drum, the feed-drum A^3 , the 80 water-tubes B^3 , connecting the feed-drum with the mud-drum, the brick arch D, extending over the fireplace from the wall of the furnace structure close to the front set of water-tubes B' , the fire-brick partition C, inclined 85 between the two sets of water-tubes $B' B^2$, and the fire-brick partition E, situated between the water-tubes B^2 and B^3 , substantially as described.

In testimony whereof I have hereunto set 90 my hand in the presence of two subscribing witnesses.

ALLAN STIRLING.
